UNITED STATES PATENT OFFICE.

WAYNE S. SEARLES, OF PROVIDENCE, RHODE ISLAND, ASSIGNOR TO UNIVERSAL OPTICAL CORPORATION, OF PROVIDENCE, RHODE ISLAND, A CORPORATION OF RHODE ISLAND.

OPHTHALMIC MOUNTING.

Application filed August 16, 1922. Serial No. 582,152.

To all whom it may concern:

Be it known that I, WAYNE S. SEARLES, a citizen of the United States, residing at Providence, in the county of Providence and 5 State of Rhode Island, have invented certain new and useful Improvements in Ophthalmic Mountings, of which the following is a specification.

This invention relates to improvements in 10 ophthalmic mountings and method of forming the same, one of the objects of this invention being to provide a method of upsetting the stock of the end piece by a swaging or molding operation so that when its 15 end piece is formed with a rearwardly projecting portion there will be no tendency of the stock to subsequently change its shape or straighten out when in use.

A further object of the invention is to 20 provide enlarged end pieces on the lens frames and to form them of a thickness greater than that of the lens-inclosing rims and arrange them to extend both forwardly and rearwardly of the planes of the side 25 edges of the lens rims for the purpose of strengthening the end pieces over those usually employed, and to so construct them that they will hold their shape and not have a tendency to straighten out, and that without 30 the necessity of applying a metal plate or lining to the same.

With these and other objects in view, the invention consists of certain novel features of construction, as will be more fully described, and particularly pointed out in the appended claims.

In the accompanying drawings:

Figure 1 is a perspective view showing a 40 non-metallic spectacle frame in which an end piece of my improved construction is shown and to which a temple member is hinged.

Figure 2 is an enlarged sectional edge view showing my improved form of end 45 piece to which the temple is shown as being hinged.

Figure 3 is an edge elevation showing the end piece as extending laterally both forwardly and rearwardly of the plane of the 50 side edges of the lens rims.

It has heretofore been found desirable in practice in order to minimize the length of the non-metallic frame, to form integral end pieces on the frame and bend these end 55 pieces rearwardly and hinge the temple

members thereto, and it is also found in practice that when these end pieces are so bent their natural tendency is to bend back or straighten out when in practical use and so move out of their designed operative position, and to obviate this difficulty I have swaged and upset the stock and thus formed or molded these end pieces into such shape as to strengthen the same and also to remove any straightening tendency, and the following is a detailed description of one construction of end piece by which these desired results may be accomplished.

With reference to the drawing, 10 designates the usual spectacle frame which is formed either wholly or in part of non-metallic material such as for instance, celluloid, zylonite, shell, or other suitable materials and to the opposite ends of this frame are formed the end pieces 11 to which are 15 hinged the temples 12.

It is found in practice that a rearwardly bent end piece formed of these non-metallic materials, has a tendency to bend back and straighten while in use and to remove this 20 straightening tendency, I have constructed an end piece with a rearward extension by a swaging or molding process and when so formed they will not change their finished 25 shape. To accomplish this in a simple and effective way, I first cut the whole frame 30 from flat stock of the thickness desired having end pieces of a width a little greater than that desired when finished and I swage 35 these end pieces under pressure by upsetting the stock and mold or force them into 40 the desired shape which is that of extending rearwardly from the plane of the inner 45 edges of the lens rims by which method of construction where the stock is so upset it 50 will remain in its molded or set position 55 and from which the tendency to straighten or bend back has been entirely removed.

In some cases I also shape the end pieces 60 so that they will have a lateral thickness greater than that of the lens inclosing 65 frames whereby the portion 13 will also extend forwardly of the plane of the front edges 14 of the lens rims and the portions 15 70 will extend rearwardly of the plane of the rear edge 16 of the lens rims by which construction 75 it will be seen that the end pieces are considerably strengthened over those of the usual shape, and that the forwardly 80 extending portion 13 serves to reinforce the 85 90 95 100 105 110

rearwardly extending portion and further prevent its straightening tendency when subjected to unusual strains.

To this rearwardly extending portion of the end piece, I have hinged the temples 12 by the hinge joint 17.

My improved frame is very strong, durable and practical in construction.

The foregoing description is directed solely towards the construction illustrated, but I desire it to be understood that I reserve the privilege of resorting to all the mechanical changes to which the invention is susceptible, the invention being defined and limited only by the terms of the appended claims.

I claim:

1. An ophthalmic mounting comprising a non-metallic frame having end pieces with a portion of the end piece extending forwardly of the plane of the forward side edges of the lens frame, to resist bending of the end piece.
2. An ophthalmic mounting comprising a non-metallic frame having end pieces of a lateral thickness greater than that of the lens rim, and having a portion of the end piece extending forwardly of the plane of the forward side edges of the lens frame, to resist forward bending of the end piece.
3. An ophthalmic mounting comprising a non-metallic frame having end pieces which extend both forwardly and rearwardly of the corresponding planes of the side edges

of the lens rims, to resist bending of the end piece.

4. An ophthalmic mounting comprising a non-metallic frame having end pieces of a lateral thickness greater than that of the lens rims and arranged to extend both forwardly and rearwardly of the corresponding planes of the side edges of said rims, whereby the end piece is strengthened against bending.

5. An ophthalmic mounting comprising a non-metallic frame having end pieces of a lateral thickness greater than that of the lens rims and arranged to extend both forwardly and rearwardly of the corresponding planes of the side edges of the said rims to resist bending, and a temple hinged to each of said end pieces.

6. An improved method of forming a non-metallic ophthalmic mounting, which consists in cutting the frame from sheet stock with end pieces thereon, and shaping these end pieces by a swaging operation with a rearwardly extending portion for hinging a temple to said end piece.

7. An improved method of forming a non-metallic ophthalmic mounting, which consists in cutting the frame from sheet stock with end pieces thereon and swaging the end pieces into a lateral thickness greater than that of the rims.

In testimony whereof I affix my signature.

WAYNE S. SEARLES.
